[57] CLAIM

I claim the ornamental design for an automotive manifold, as shown and described.

DESCRIPTION

FIG. 1 is a perspective looking from the upper front left of the automotive manifold incorporating my new and novel design;

FIG. 2 is a top plan view of the automotive manifold shown in FIG. 1;

FIG. 3 is a front elevation of the automotive manifold shown in FIG. 1;

FIG. 4 is a rear elevation of the automotive manifold shown in FIG. 1;

FIG. 5 is a right side view of the automotive manifold shown in FIG. 1;

FIG. 6 is a left side view of the automotive manifold shown in FIG. 1; and,

FIG. 7 is a bottom plan view of the automotive manifold shown in FIG. 1.
